UNITED STATES PATENT OFFICE.

ERNST ARNOLD, OF READING, PENNSYLVANIA.

HYDRAULIC TOY.

1,299,897.

Specification of Letters Patent.

Patented Apr. 8, 1919.

Application filed April 4, 1916. Serial No. 88,767.

To all whom it may concern:

Be it known that I, ERNST ARNOLD, a citizen of the United States, residing at Reading, in the county of Berks and State of 5 Pennsylvania, have invented certain new and useful Improvements in Hydraulic Toys, of which the following is a specification.

My invention relates to toys adapted to 10 be educative as well as amusing; and it consists in combining a fountain basin and jet-pipe with liquid-pressure and air-pressure chambers, so as to produce an attractive and interestingly puzzling device involving 15 well-known scientific principles in its automatic operation; as fully described in connection with the accompanying drawing, and clearly defined in the claim.

The drawing is a sectional elevation showing 20 my improved device as preferably constructed.

The construction indicated is very light and economical, involving the use of sheet metal and piping mainly or exclusively; 25 the casing *a* being of tubular form, with suitably flared top and bottom portions *b* and *c*, and having lower spaced-apart partitions *d* and *e* tightly secured therein to form a bottom air-pressure chamber *f*, and an up- 30 per partition *g* and dished cover-plate *h* also tightly secured and arranged to form between them a closed water-reservoir *k* extending around and below the fountain-basin *m* formed by the dished cover-plate. 35 A vertical pipe *n* rigidly connects the basin *m* to the air-pressure chamber *f*, passing tightly through the partitions *g* and *e* to near the bottom of the chamber *f*, and serving to conduct the liquid from basin *m* to 40 said chamber as controlled by a plug-valve *p* or the like. The said pipe *n* is coiled as shown to retard the gravitation of water from the basin *m* to the chamber *f*, and in that way prolong the operation of the apparatus. 45 Another pipe *r* rigidly connects the air-pressure chamber *f* with the reservoir *k*; extending from the top of chamber *f* into a screw-capped filling-and-emptying opening *s* of the reservoir as indicated, and 50 serving to conduct compressed air from the top of chamber *f* to the top of reservoir *k*.

The jet-pipe *t* is centrally secured to the dished cover-plate *h*, with its open lower end depending into the reservoir *k*; the partition *g* which forms the bottom of the latter

being depressed at its center as indicated so that the last remaining liquid in the reservoir will be forced into the jet-pipe. The nozzle *u* may be changed so as to vary the size and height of the fountain jet therefrom in order that the descending water from the jet will operate a miniature water-wheel *v* suitably mounted upon the basin as indicated.

When the basin *m* and reservoir *k* are 60 filled with water or other liquid and the screw-cap tightly closed, it will be readily seen that upon removal of the plug-valve *p* the liquid will flow from the basin into the lower chamber *f*, and cause a flow of compressed air through pipe *r* into reservoir *k* whereby the liquid in the latter will be forced through the jet-pipe *t* as determined by the head of liquid in the basin and the supply in the reservoir. As the jet discharges into the basin the head is substantially maintained; and the reservoir being in close contact with the basin there is only a minimum variation in the height of the jet produced. This action is automatically 65 continued until the entire supply of liquid in the reservoir has been discharged, which may require an hour or longer as determined. In order to renew the operation the filled lower chamber must be emptied and the 70 reservoir refilled, both of which are effected through the single capped opening *s* as shown, though separate means may be provided for emptying the lower chamber if desired. While the operation is simple it 75 is interestingly puzzling to the juvenile mind and the device is stimulatively educational as well as pleasing and amusing. The construction specifically described may be 80 readily modified in detail without departing 85 materially from the invention.

What I claim is:

A hydraulic toy comprising a casing, a chamber in the lower portion of the casing, a chamber in the upper portion of the casing, 100 the inner wall of the latter chamber forming a basin and said chamber having in the upper wall a screw-capped filling and emptying opening and also having a central depression in its bottom wall, a discharge nozzle communicating at its lower end with the interior of said depression and extending upwardly through the basin wall, a conduit leading upwardly from the upper portion of the lower chamber and having its eduction 105 110

orifice disposed in the screw-capped filling opening of the upper chamber, a pipe leading downwardly from the bottom of the basin to the lower portion of the lower chamber and having a coiled intermediate portion adapted to retard the passage of water from the basin to the lower chamber,

and movable means for closing the induction orifice of said pipe to retain water in the basin until it is desired to bring about 10 an operation of the toy.

In testimony whereof I affix my signature.

ERNST ARNOLD.
